UNITED STATES PATENT OFFICE.

ABEL KLUGE AND ENEVAL KLUGE, OF ST. PAUL, MINNESOTA, ASSIGNEES TO BRANDT-JEN AND KLUGE, INC., OF ST. PAUL, MINNESOTA, A CORPORATION OF MINNESOTA.

SHEET-DELIVERING DEVICE.

Application filed May 7, 1923, Serial No. 637,138. Renewed August 3, 1925.

Our invention relates to improvements in sheet delivering devices.

Its object is to supply a device of this kind particularly, though not exclusively, for taking printed sheets from the platen of a printing press and releasing the same upon a collecting rack or table.

A further object is to provide a sheet delivering device for platen presses including a pneumatic grip and novel means for directing the same through a cycle of movement including a sharp downward approach to a printed sheet on the platen, said means permitting of the swinging of said grip out of its operative path and into inoperative position permitting of unobstructed access to the press parts.

Another object is to provide mechanism for moving a pneumatic grip inward to sheet receiving position and outward to sheet discharging position, that part of said mechanism serving to carry the grip inward being adapted to yield to avoid injury to parts in case the grip is obstructed in its inward travel and also, to permit of the retraction of said grip out of normal position in its cycle of movement.

An additional object is to provide a pneumatic sheet delivering device including novel driving and suction relieving means co-operating to enhance dependability of operation and simplicity of construction.

With the foregoing and other objects in view, which will appear in the following description, the invention resides in the novel combination and arrangement of parts and in the details of construction hereinafter described and claimed.

In the drawings, Fig. 1 is an elevational view illustrating a platen press and a sheet delivering device applied thereto and embodying our invention; Fig. 2 is a detail sectional view taken on the line 2-2 of Fig. 1; Fig. 3 is a sectional view taken on the line 3-3 of Fig. 2; Fig. 4 is a perspective view in detail of a portion of our improved device and Fig. 5 is a diagrammatic illustration showing the path of the pneumatic grip in relation to the platen and sheet collecting rack or table of the printing press.

Referring to the drawings, we have illustrated, in Fig. 1, a platen press A of ordinary design. The improved sheet delivering mechanism applied to said press includes a

bracket 10 suitably secured to the press frame in position reaching rearwardly from the platen 11. A track B, comprising a rod 12 and bar 13 joined in spaced parallel relation at their ends by blocks 14 and 15, swings vertically on the bracket 10, the block 14 being pivoted on a bolt 16 in the rear of the bracket 10 and the block 15 slideable vertically in an upright guide c secured to the forward end of said bracket. A carriage D moves back and forth on the track B. This carriage consists of a sleeve 17, slideable on the rod 12 and a saddle 18 joined by a web 19 with said sleeve and slideable on the bar 13. A support E carried by the sleeve 17 includes a clamp 20 embracing said sleeve, said clamp being gripped on said sleeve by means of a clamping bolt 21. Said support E also includes a rod 22 secured at one end thereof in a boss 23 on the clamp 20. Upon loosening the bolt 21, the clamp 20 may be turned on the sleeve 17 to swing the rod 22 between operative position (solid lines, Fig. 4) and inoperative position (dotted lines, Fig. 4). While the tightening of the clamping bolt 21 serves to firmly grip the clamp 20 on said sleeve, we have arranged a stop 24 on said clamp to engage the web 19 in horizontal, operative position of the support E. This stop automatically locates the support horizontally and minimizes the necessary binding force of the clamping screw 21. A clamp 25 on the rod 22 together with a metallic tube 26, carried by said clamp, and cross-head 27 on said tube, comprise a mounting F for suction grips 28. These grips, slidably supported on said cross-head 27, communicate through flexible tubes 29 with the metallic tube 26, which in turn, communicates through a flexible tube 30 with a suction conduit 31.

Means, soon to be described, reciprocate the carriage D on the track B and raise and lower the forward end of said track to direct the grips 28 in paths with respect to the platen 11 and sheet collecting rack 32, as shown in Fig. 5. In said figure, it will be observed that the grips 28 move toward the platen 11 in an elevated path 33° curved sharply downward at its forward end. This abrupt drop of the grips 28 brings the same almost directly downward upon a sheet on the platen and makes certain the grasping thereof, which result might not obtain were

the movement of the grips otherwise in respect to a curled or warped sheet. It will also be observed that the return path 33^b of the grips 28 is inclined only slightly upward 5 from the plane of the platen 11, thence rise abruptly in a path 33^c to starting position. The slightly upwardly inclined path 33^b of the grips 28 provides for clearing the platen, yet locates said grips at a low elevation for 10 the discharge of sheets upon the collecting rack 32.

The turning of the support E from horizontal, operative position to upright, inoperative position, carries said support, mounting F and grips 28 out of the way of an operator having access to the press parts. The clamp 25 provides for longitudinal adjustment of the tube 26 thereon, whereby the reach of the grips 28 on the platen 11 may 20 be varied. Said clamp 25, being capable of angular and longitudinal adjustment on the rod 22, also provides for shifting the grips 28 laterally of the platen 11 and, further provides for locating said grips in elevation 25 to bring them into proper sheet taking relation.

The carriage D is reciprocated through the following means: An upright lever 34 pivots at its lower end on a bracket 35 secured to 30 the press. A link 36 joins the upper end of said lever 34 with the sleeve 17 of the carriage D. A bell-crank G rockably mounted on the press A has one arm 37 thereof joined by a link 38 with said lever 34. The other 35 arm 39 of the bell-crank G has a roller bearing 40 at its free end, which rides upon the surface of a cam 41. This cam turns on a stud 42 reaching outward from the side of the press frame and is driven from the press 40 gear 43 through intermediate gears 44 and 45. An expansion spring 46, bearing against an extension 47 on the bell-crank G, moves the carriage D forward, when the surface of the cam 41 recedes from the roller 40, but 45 yields to permit the rearward movement of said carriage by said cam. In this connection, it may be noted that the yielding power of the spring 46 in moving the carriage D forward is attended with safety against the 50 breakage of parts in case the grips 28 or carrying mechanism is obstructed in their forward movement. Said spring 46 also permits of the retraction of the carriage D out of its normal relation, which is at times 55 carried out in addition to the raising the support E, preparatory to make-ready operations. A hook 48 swung on the bolt 16 in the bracket 10 is arranged to catch a pin 49 on the carriage D and hold the same back 60 against the action of the spring 46. The track B tilts downward by gravity, but is elevated by power derived from the press. A lifter rod 50 is attached at its upper end to a pin 51 reaching outward from the block 65 15, through a slot 52 in the outer flange 53

of the guide c. The lower end of said rod is attached to the free end of a lever 54, which is pivoted on the press frame. Medially of this lever 54 is a roller 56 arranged to ride a cam 57 secured to the cam 41. The cams 41 and 57 are timed with respect to the press and shaped to cause the reciprocation of the carriage D and the tilting of the track B in a manner directing the grips 28 as hereinbefore explained. 75

A valve mechanism associated with the suction conduit 31 for admitting air thereto is illustrated in Figs. 1, 2 and 3. A hollow block 58, secured to the bracket 35, communicates through a nipple 59 with the conduit 31. A hollow stem 60 rising from said block has a seat 61 at its upper end for a ball valve 62, which is guided from said seat by means of a cap or cage 63. A lever 64, pivoted at one end on the lever 34, has a looped valve lifting member 65 at its free end occupying position beneath the ball valve 62. The head 66 of a bolt 67, threaded upward through the lever 64 and supplied with a lock nut 68, provides a fulcrum for engagement with the curved surface of a boss 69 on the bracket 35. The engagement of this fulcrum with said boss 69, upon the rearward throw of the lever 34, causes the lever 64 to lift the ball valve 62 from its seat 61. When thus unseated, the valve admits air to the conduit 31 and destroys the gripping action of the suction grips 28. Being adjustable, the bolt 67 may be set to cause the release of sheets by the grips 28 earlier or later in the rearward throw thereof, as may be desired. 95

Changes in the specific form of our invention, as herein disclosed, may be made within the scope of what is claimed without departing from the spirit of our invention. 105

Having described our invention, what we claim as new and desire to protect by Letters Patent is:

1. The combination with a platen press, of a bracket thereon, a track reaching back from the platen and pivoted at its rear end on said bracket, a carriage slideable on said track, a support swung on said carriage and movable from operative horizontal position 110 into inoperative upright position, a mounting adjustable angularly and longitudinally of said support, a pneumatic grip on said mounting, a suction conduit communicating with said grip, a valve adapted, when open, to admit air to said conduit, means for reciprocating the carriage on said track, means for tilting the track upward and downward, said means being co-ordinated with the press mechanism and with each other to direct the grip inward in a path pitching sharply downward at its forward extremity to sheet taking position on the platen, thence rearward to depressed sheet releasing position 115 back of said platen, and a device actuated by 120

- said carriage reciprocating means for opening said valve at sheet releasing position of the grip.
2. The combination with a platen press, of a bracket thereon, a track reaching back from the platen and pivoted at its rear end on said bracket, a carriage slideable on said track, a suction grip carried by the carriage, means for reciprocating the carriage on said track and means for tilting the track, said means being co-ordinated with the press and with each other to direct the grip inward in an elevated path pitching sharply downward at its forward extremity to sheet taking position on the platen, thence rearward to depressed sheet releasing position back of the platen.
3. The combination with a platen press, of a suction grip movable back and forth between position for taking sheets from the platen and position for releasing the same at the rear thereof and means co-ordinated with the press for directing the grip to receiving position in a forward path first substantially paralleling the platen then pitching sharply downward at the end thereof and to releasing position in a rearward path beneath said forward path.
4. The combination with a platen press, of a bracket thereon, a track extending along one side of the platen and pivotally supported at one end thereof to swing vertically, a carriage slideable on said track, a grip carried by said carriage, means for reciprocating the carriage on said track, means for tilting the track, said means being co-ordinated with the press and with each other to direct the grip forward in one path to sheet taking position on the platen then backward in another path to sheet releasing position.
5. The combination with a platen press, of a track extending along one side of the platen, a carriage slideable on the track, a support hinged on the carriage and tiltable upward from horizontal operative position into elevated inoperative position, a suction grip mounted on said support, means for reciprocating the carriage on said track, said means being co-ordinated with the press to direct the grip forward to sheet taking position on the platen and backward to sheet depositing position at the rear of the platen.
6. The combination with a platen press, of a track extending along one side of the platen, a carriage slideable on the track, a support hinged on the carriage and adapted to be swung thereon out of operative position into position of disuse not obstructing access to the platen, a grip carried by said support, and means for reciprocating the carriage on said track, said means being co-ordinated with the press to shift the grip forward to sheet taking position on the platen and backward to sheet depositing position at the rear of the platen.
7. The combination with a platen press, of a support, a grip carried thereby, and a mounting for the support movable to direct the grip toward the platen to sheet taking position and away from the platen to sheet depositing position, the support being movable on said mounting from operative position into position of disuse to permit of access to the platen unobstructed by said support and grip.

In testimony whereof, we have signed our names to this specification.
